SAFETY HOOK

Filed April 8, 1925

Inventors:

David Patterson Cromwell
Patterson Cromwell

UNITED STATES PATENT OFFICE.

DEWITT PATTISON CROMWELL, OF HUBBARD, OHIO, AND PATTISON CROMWELL, OF TERRE HAUTE, INDIANA.

SAFETY HOOK.

Application filed April 8, 1925. Serial No. 21,539.

To all whom it may concern:

Be it known that we, DEWITT PATTISON CROMWELL and PATTISON CROMWELL, citizens of the United States, and residents, respectively, of Hubbard, in the county of Trumbull and the State of Ohio, and of Terre Haute, in the county of Vigo and the State of Indiana, have invented a new and useful Safety Hook, of which the following is the specification.

The invention pertains to an improved method for the handling of steel rails, ties, piling, cribbing or any structural material that is used in the construction of railroads and commercial construction, or in the repairs of same; and the objects of the invention are, first, to provide a safe method of handling the above material, second, to decrease the costs of handling the same; and, third, to provide a device that is generally useful to this class of construction or repair, that is, a machine that does several classes of work along these lines, such as removing objects such as ties, piling or telephone poles that are submerged under water.

One form of the invention is illustrated in the accompanying drawing in which Figure 1, is a vertical cross-section of the entire machine, certain parts being shown in elevation; Figure 2, is a side view of the cylinder; Figure 3, is an elevational view of the double hooks and counter-weight; and Figure 4, is a top plan view of the cylinder.

The cylinder, 1, is the outside casing of the machine and it is also the guide and holder for the counter-weight, 2, and the double-hook, 8, —8, 9, mechanism. Through the lower end of the cylinder, 1, is the stationary shaft, 10, upon which pivots the double hooks, 8, —8, 9. This cylinder, 1, is provided with the lifting cap, 3.

The lifting rod lug, 6, is keyed to the lifting rod, 5, by the key arrangement, 15. The lifting rod, 5, is connected to the connecting links, 11 and 11, —12 and 12, by the connecting pin, 13, and the connecting links are

connected to the double hooks by the connecting pins, 14. The double hooks, 8, —8, 9, pivot on the shaft, 10, which, being stationary, also supports the counter-weight, 2, 50 when hooks are open.

The machine in operation is used on any steam or electric crane having a holding and closing cable. The holding cable supports the machine by the lifting lugs, 7, 7, and the double hook, 8, —8, 9, will be in the open position. The closing cable is attached to the lifting rod lug, 6, and when this cable is tightened and the holding cable is slackened off a trifle, the hooks will close on any desired object. When this object is released, the holding cable is held tight and the closing cable is slackened off and the counter-weight, 2, drops of its own weight and opens the double hooks. 60 65

We do know that prior to our invention, common tongs and cable slings were used to handle railroad ties, rails and piling.

However, we claim:

1. In a safety hook construction the combination of a pair of parallel hooks pivotally mounted in spaced relation intermediate their ends and movable as a unit, an oppositely directed and similarly mounted hook positioned intermediate said unitarily movable hooks and having the same pivotal axis, and a weighted toggle linkage normally maintaining said hooks in open relation and actuatable in opposition to the weighting thereof for closing said hooks. 70 75 80

2. In a safety hook construction, the combination of a supported tubular casing, a rod slidably supported therein, a combination guide and counter weight carried by the rod and slidably supported within said casing for guiding said rod, a fixed pivot supported by said casing, hooks pivotally supported upon said pivot, and toggle links within and protected by the casing and pivotally connected to the hooks and the rod. 85
